Patented June 29, 1920.

FIG. 1

FIG. 2.

INVENTOR
Herbert W. Knapp

BY
George J. Thorpe
ATTORNEY

UNITED STATES PATENT OFFICE.

HERBERT W. KNAPP, OF KANSAS CITY, MISSOURI.

WATER-LEVEL-SIGNALING ATTACHMENT FOR MOTOR-CARS.

1,344,904.

Specification of Letters Patent. Patented June 29, 1920.

Application filed May 14, 1917. Serial No. 168,618.

To all whom it may concern:

Be it known that I, HERBERT W. KNAPP, a citizen of the United States, residing at Kansas City, in the county of Jackson and 5 State of Missouri, have invented certain new and useful Improvements in Water-Level-Signaling Attachments for Motor-Cars, of which the following is a specification.

This invention relates to water level signaling equipment and is designed more particularly for signaling to the driver of a motor car when the volume of water in the radiator falls to a level suggestive of the advisability of the replenishment to guard 10 against over-heating of the engine, and my object is to produce an attachment of the character outlined, which will operate efficiently and which can be manufactured and applied to motor cars at a small cost. With 15 this object in view the invention consists in certain novel and peculiar features of construction and combinations of parts as hereinafter described and claimed, and in order that it may be fully understood reference is 20 to be had to the accompanying drawing, in which:

Figure 1, is an elevation chiefly in vertical longitudinal section of a part of a motor car equipped with a signaling attachment embodying my invention.

Fig. 2, is an enlarged central vertical section of a part of the attachment.

In the said drawing, 1 indicates a vessel adapted for securement in any suitable manner, not shown, to the front side of the dash D of an automobile, H indicating the hood and R the radiator of the car.

The vessel is provided with an opening 2 in its bottom and with an air vent 3 at the 40 top. Near the top which is also provided with a partition 4 having an opening 5 vertically above opening 2, and extending loosely through and guided in said openings is a rod 6 equipped with a valve 7 for normally engaging the partition 4 around the opening 5 to close said opening to the passage of air or water. Near its lower end the rod 6 is provided with a collar 8 to engage the bottom of the vessel and limit downward movement thereof and of the float 9 secured upon the rod 6 within the vessel.

The rod is equipped at its upper end above the partition 4 with a laterally projecting spring contact 10 adapted to be 45 spaced above a contact 11 when the valve 7 is closing the opening 5, that is when the

float is elevated by water within the vessel, as hereinafter more particularly explained. When said float occupies its depressed position and the valve therefore its open position, the contact 10 is engaged with contact 11 and a circuit is completed which apprises the driver of the car of the fact that the water supply in the radiator is undesirably 60 low.

The contact 11 is electrically connected to a binding post 12, and said parts are insulated as at 13 from the vessel, the binding post being disposed exteriorly of the vessel and adjacent a binding post 14 mounted on 70 the vessel and electrically engaged therewith.

15 is a pipe-way connecting the bottom of the vessel around opening 2 with a T-coupling 16 secured on the drain pipe P of the 75 radiator and above the pet-cock C of said drain pipe.

17 is an incandescent lamp or other signaling device secured to the dash at the rear side thereof and said lamp is in circuit with a storage battery or other electric current generator 18 forming a part of the equipment of the car, and with the binding post 12, the binding post 14 being also in circuit with said source of electric current supply, a diagrammatic view of the circuit being indicated in Fig. 1.

The float is of such weight that it will not rise and close the valve 7 until the radiator has been charged with the minimum 90 quantity of water with which it is desirable to operate the car, water in excess of said amount which is poured into the radiator simply tending to hold the float elevated with greater force, and as long as 95 the float is elevated the circuit is broken through the lamp by the contacts 10 and 11, this relation of said contact continuing until the volume of water in the radiator and hence in the vessel falls sufficiently low 100 to permit the float to descend until contact 10 engages contact 11. Immediately this engagement between said contacts takes place, the circuit is completed through the lamp and the driver is apprised of the 105 fact that the supply of water in the radiator should be replenished.

From the above description it will be apparent that I have produced a simple and efficient attachment for signaling the 110 driver of a car regarding the quantity of water in the radiator, and it will be noted

that the attachment is of simple and compact construction, is not liable to get out of order and with the exception of the lamp, is completely hidden from view.

5 While I have illustrated the preferred construction and arrangement of the attachment, it is to be understood that I reserve the right to make all changes in form, proportion, detail construction and organization as properly fall within the spirit and scope of the appended claim.

I claim:

15 In a water level signaling attachment for motor cars and the like, a vessel provided with a bottom opening, a partition provided with an opening vertically above said bottom opening, a vertical rod extending through said bottom opening and the opening of the partition and provided with a laterally-pro-

jecting spring contact 10, a valve secured to 20 said rod for closing or opening the opening in the partition from below the same, a float secured upon said rod within the vessel for imparting closing movement to said valve when the vessel contains the requisite 25 quantity of water and for opening said valve when the water level falls below the requisite quantity, a pair of binding posts secured to the vessel one in electrical connection therewith and the other insulated 30 therefrom, and a contact 11, extending from the last-named binding post into the vessel above the partition thereof, for engagement by contact 10, when the float falls below a predetermined level.

35 In testimony whereof I affix my signature.

HERBERT W. KNAPP.
